BATHTUB ATTACHMENT

John Kapella, Chicago, Ill.

Application March 14, 1935, Serial No. 11,098

5 Claims. (Cl. 4—185)

The present invention relates to bath tub attachments and has for its main object the provision of a portable, simple in construction and inexpensive attachment preferably made out of a tubular metallic material, preferably in a rectangular shape, which may be used for positioning transversely of a bath tub for supporting washing pans, laundry, etc., or which may be utilized as a seat on placing thereon a suitable board.

A further object of the present invention is the provision of an attachment consisting of a rectangular frame made out of a single tubular strand suitably joined together for the purposes hereinabove specified.

A still further object of the present invention is a provision of a rectangular frame for the purposes indicated having thereon a plurality of bushings slideable and adjustable thereon whereby the frame may be rested upon oppositely disposed sides of a bath tub.

A still further object of the present invention is a provision of a frame hereinabove indicated and for the purpose hereinbefore set forth, which may be covered or coated with rubber substance, and which may be made out of one piece of material, suitably formed and joined by its ends to provide a rectangular frame.

With the above general objects in view and others that will appear as the invention is better understood, the same consists of the novel construction, combination and arrangement of parts hereinafter more fully described, illustrated in the accompanying drawing and pointed out in the appended claims.

In the drawing forming a part of this application and in which like designating characters refer to corresponding parts throughout the several views,

Fig. 1 is an elevational perspective view of the present device;

Fig. 2 is a transverse cross-sectional view of a bath tub with a side view of the present device in an operative position upon the bath tub;

Fig. 3 is a cross-sectional view on line 3—3 of Fig. 2;

Fig. 4 is a cross-sectional view through a portion of the device showing the construction of a joint in the present device;

Fig. 5 is a transverse cross-sectional view of another form of a bath tub with the present device shown in an operative position thereon, and illustrating another manner of using the present device in connection with a different style of a bath tub; and

Fig. 6 is a cross-sectional view through one side of the frame of the device and one bushing used in connection therewith, the view having been taken on line 6—6 of Fig. 1.

The present device best illustrated on Fig. 1 consists of a rectangular frame having a pair of longer sides 10 and a pair of shorter parallel sides 11, the frame having been made out of a tubular metallic material 12 and joined together at 13 by means of a cylindrical lug 14 positioned across said joint 13 and within the meeting ends of tube 12. The two ends of said tube 12 and cylindrical lug 14 are riveted by a pair of rivets 15 for the purpose of providing a firm and rigid joint. Said joint 13 including lug 14 is preferably positioned at one of the shorter parallel sides of the device, indicated by dotted lines on Fig. 1.

Before the tubular rod 12 is bent into a rectangular frame and joined together as hereinbefore indicated, a pair of bushings 16 are placed at the portion of the parallel rod 12 which on forming said rod into a frame, would ultimately constitute the longer parallel sides of the frame. Said bushings 16 may be made out of hard rubber, fiber, or any other suitable material.

The surface of the frame best illustrated on Fig. 1 may be covered with a coating of rubber 17, and this may be done either by sheeting the metallic cylindrical rod 12 by a rubber hose prior to the formation of the former into a rectangular frame shown on Fig. 1, or if preferable the completed frame may be rubberized upon the frame having been formed and completed. In either event bushings 16 would longitudinally frictionally slide upon the longer parallel side of the rectangular frame.

As is obvious from the hereinabove description the pair of bushings adjacent one shorter side of the rectangular frame may be shifted towards the other opposite pair of bushings 16 so that the said pairs of bushings may be either shifted towards or away from each other, depending upon the width of the bath tub.

As shown on Fig. 2 bath tub 18 is one of the conventional types having outwardly flared flange 19 constituting the upper edge of the bath tub. In this type of a bath tub bushings 16 may be shifted to coincide with the oppositely disposed portion of edge 19 transversely of the bath tub, in which case said bushings 16 would form seats fitting the upper edge of the bath tub upon which frame of the present device would firmly rest upon the bath tub in a transverse relation therewith.

Fig. 5 illustrates another form of a bath tub of the style wherein one longer side of the bath tub contacts with wall 20 of a dwelling, and in which type the adjacent side of the bath tub 21 has an outward horizontal rest 22 joining wall 20. The other side of the bath tub is formed into a skirt side 23 extending from the adjacent wall 24 of the bath tub and forming a bend 25 providing the top edge of that side of the bath tub, said bath tub 21 and rest 22 being usually on the same plane. In this latter type of a bath tub the present device may be rested thereon directly, one shorter parallel side thereof and adjacent ends of the longer parallel sides 10 resting directly upon rest 22 and the opposite end portions of said parallel longer sides 10 contacting and resting directly upon the adjacent top 25 of the opposite side of bath tub 21. In this latter form of bath tub bushings 16 may be shifted to contact the inner sides of the bath tub adjacent its top as clearly shown on Fig. 5, whereby said bushings may prevent shifting of the frame longitudinally thereof upon the bath tub. It is observed that said bushings 16 by virtue of frictional contact with the sides of the frame do not readily slide, hence in the application of the frame upon the bath tub of the type shown on Fig. 5 said bushings 16 would prevent sliding of the frame longitudinally thereof or transversely of the bath tub and prevent slipping of the end of the frame which reposes upon rest 22 adjacent wall 20.

It is further observed that each of said bushings 16 is concaved, being narrower at its center and having its opposite ends outwardly flaring, so as to engage and provide a more perfect fit at the upper edges of bath tub 18 shown on Fig. 2 when said bushings 16 rest upon said bath tub.

From the hereinabove description it will be apparent that washing pans may be positioned between the longer parallel side of the frame, and such washing pans may be held therebetween by the usual flange of a washing pan which would directly rest upon said sides 10. If necessary, however, board 26 may be placed upon central portions of said longer parallel sides 10 of the frame, and said board 26 may be preferably provided on its underside with a pair of parallel strips, interposed between said longer parallel sides 10 of the frame in such a manner that the outer side of each of said strips 27 would contact with the inner portion of the periphery of the adjacent side 10 of the frame, as is clearly indi-

cated on Fig. 3. This arrangement would prevent shifting of board 26 laterally or transversely of the frame.

While there is described herein a preferred embodiment of the present invention, it is nevertheless to be understood that minor changes may be made therein without departing from the spirit and scope of the invention as claimed.

What I claim as new is:

1. A bath tub attachment comprising a frame 10 made out of a single strand of material wherein the ends thereof are rigidly joined, and a plurality of bushings positioned upon said frame adapted for sliding thereon.

2. A bath tub attachment comprising a rectangular frame, including a pair of longer and a pair of shorter parallel sides, said frame being made out of a single strand of material having its ends rigidly joined, and a plurality of bushings positioned upon the longer parallel sides of said frame 20 and adapted for longitudinal sliding upon said sides.

3. A bath tub attachment comprising a rectangular frame having a pair of shorter and a pair of longer parallel sides, said frame being formed 25 out of a single strand of material having its ends rigidly joined, an abrasion-proof envelope upon said frame, and a plurality of bushings made out of material analogous to the material in said envelope, said bushings being adapted for longitudinal frictional sliding upon said frame.

4. A bath tub attachment comprising a frame made out of a single tubular strand of material and including a pair of longer and a pair of shorter parallel sides, the ends of said strand forming 35 one of the shorter sides of said frame, a lug entering both of said ends to form a joint therebetween, and rivets at each of said ends passing through said lug for forming a rigid joint between said ends, and a plurality of bushings positioned 40 for sliding movement upon the longer parallel sides of said frame.

5. A bath tub attachment comprising a rectangular frame including a pair of shorter and a pair of longer parallel sides, said frame being made 45 out of a single strand of material having its ends rigidly joined, and a plurality of bushings positioned upon a pair of oppositely disposed sides of said frame and adapted for longitudinal sliding movement thereon.

JOHN KAPELLA.
